DAMPER

Frank F. Jackson, Cleveland, Ohio, assignor of one-third to Emerson M. Williams and one-third to Harvey M. Smith, both of Cleveland, Ohio

Application April 17, 1931. Serial No. 530,921

5 Claims. (Cl. 126—285)

This invention, relating as indicated to dampers, has particular reference to a form of construction designed to be employed as a damper in flues or stacks conducting hot gases from or to furnaces.

It is well known to those familiar with the art that considerable difficulty has been experienced in the past in the construction of dampers due to the intense heat to which such dampers are subjected. Incidental to the intense heating to which the dampers are subjected when disposed in the path of the heated gases and further, due to the fact that usually only a portion, i. e., the lower end of the damper projects directly into the path of hot gas flow, internal stresses are set up; which, were the damper made in one piece, would cause a cracking or similar depreciation of the damper. In order to obviate this premature failure of dampers, it has been common practice to form such dampers of a plurality of sections usually arranged in vertically contiguous relation so as to reduce to a minimum the formation of internal stresses and to facilitate the replacement and repair of the portions of the damper which most quickly deteriorate.

This sectional form of construction for the dampers has led to a number of difficulties usually centering about the means employed for maintaining the sections in proper assembled relation. A further difficulty which has been encountered in the operation of sectional dampers has been the tendency of such constructions to warp under the intense heat and due to such warping, cause a binding between the edges of the damper and the guide means associated therewith.

It is among the objects of my invention to provide a form of damper construction which shall eliminate all of the above-named undesirable characteristics. Other objects of my invention will appear as the description proceeds.

To the accomplishment of the foregoing and related ends, said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a part elevational, part sectional view

showing the apparatus comprising my invention and its associated supporting guides.

Fig. 2 is an elevational view of the back side of the damper illustrated in Fig. 1.

Fig. 3 is a transverse sectional view of the apparatus illustrated in Fig. 1, taken on a plane substantially indicated by the line 3—3.

Fig. 4 is a vertical section view of a portion of the apparatus illustrated in Fig. 1, taken on a plane substantially indicated by the line 4—4 and Fig. 5 is a fragmentary sectional view drawn to an enlarged scale of a portion of the apparatus illustrated in Fig. 1 taken on a plane substantially indicated by the line 5—5.

Referring now more specifically to the drawing and more especially to Fig. 1, the damper construction herein illustrated is designed to be employed as a stack or flue damper and as is well known to those familiar with the art, such dampers are usually vertically reciprocable in guide means such as channels 1, which may be built in or otherwise associated with the walls of the flue across which the damper is designed to move.

The damper generally indicated at 2 in Figs. 1 and 2 constructed in accordance with the principles comprising my invention is designed to be supported dependently from a rod or shaft 3 which is employed to support and manipulate such damper. The construction comprising my invention is divided into a plurality of vertically adjacent sections such as 3, 4 and 5.

It will be noted from the disclosure of Figs. 1 and 2 that a plurality of intermediate sections such as 4 may be employed in order to provide a damper of the required vertical extent. The intermediate members 4 have head and bottom members 3 and 5 respectively associated therewith for the purposes hereinafter more fully explained. The elements 3, 4 and 5 comprising sections from which the damper is constructed will preferably be formed of a suitable heat resisting alloy and are provided with horizontally extending concavo-convex reinforcing portions 6 which may further be reinforced by vertically extending ribs 7. These reinforcement portions, as above indicated, are concave on one side of the damper members and extend convexly on the opposite side thereof and in combination with the vertically extending ribs produce a structure having strength and a rigidity under the severest strain not equalled by any form of construction heretofore employed.

The sections 3, 4 and 5 are secured in proper assembled relation in the manner most clearly

illustrated in Figs. 4 and 5. As most clearly illustrated in these figures and more especially in Fig. 4, the adjacent edges 8 and 9 of the vertically adjacent members have T-shaped grooves 5 formed on the adjacent faces in which is mounted an I-shaped member 10. This I-shaped member will have a web of sufficient vertical extent so that a slight space will be left between the adjacent members 3, 4 and 5 and the groove 10 within which such I-shaped members are engaged will likewise be provided with sufficient tolerance so that the lower member is movable and independently supported from the next adjacent upper member.

15 In order to prevent axial movement of the I-shaped members 10 relatively to the vertically adjacent members joined thereby, I provide locking means such as are most clearly illustrated in Fig. 5. As illustrated in this figure apertures are 20 provided in the walls bounding the T-shaped grooves in which the I-shaped member is positioned in which apparatus blocks such as 11 and 12 are positioned and united by means of a screw such as 13. For purposes of convenience, it 25 has been found that by providing the block 11 with a recess space 14 into which the terminal of the screw 13 projects and then by filling such recess with molten metal such as 15, preferably deposited by means of electric welding and the 30 like, the screw 13 is properly secured to the block 11. The screw 13, i. e., the shaft thereof passes through the aperture provided therefor in the web of the I-shaped member 10 and is maintained in proper position by means of a nut such as 16. This engagement by the bolt 13 of the 35 I-shaped member 10 and the restraint of the bolt against movement by means of the blocks 11 and 12 effectively prevents relative movement between such I-shaped member and the damper 40 sections connected thereby.

The bottom member 5 will, of course, have a plain bottom edge instead of being provided with a groove as are the bottom edges of the other damper sections and such bottom section will 45 preferably be much shallower than the other sections for the reason that it is this portion of the damper which projects into the path of the hot gases passing through the flue and by reducing the vertical extent of such bottom section, 50 the internal stresses in the damper are appreciably reduced and this reduction in the size of the bottom member has a further advantage in that the same may be replaced when deteriorated due to the action of the gases at a minimum of 55 cost.

The top section 3 may be formed in any manner most desirable to properly sustain the body of the damper and such top section being as hereinbefore indicated also provided with suitable reinforcing projections and ribs serves as an anchor for the balance of the apparatus. The top member 3 is, of course, provided with suitable means such as an abutment 17 which has an aperture which serves as an anchor for the rod or bar 3 supporting the damper.

It will be noted from the foregoing description that the damper comprising my invention consists of a plurality of vertically adjacent de-

pendedly supported sections which, due to the tolerance between the edges of such sections, enables the several parts of the damper to move relatively to each other to permit movement of the damper within the guides 1 irrespective of any slight irregularity caused by warping of the damper itself. This relative movement between the several parts of the damper is made possible without any sacrifice of effectiveness for the purpose for which it is designed, due to the fact that the weight of the successive parts causes the proper sealing between the several portions of the I-shaped member 10 and the grooves within which it is mounted so that an effective seal across the flue or stack is provided by the assembled structure.

Other advantages incidental to the employment of the apparatus hereinbefore described are believed to be so apparent from the description and the disclosure in the drawing that a further enumeration of such advantages is unnecessary for those familiar with the art.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a damper, the combination of a plurality of vertically adjacent members, said members having longitudinally extending grooves on adjacent edges, and means engaged by said grooves whereby each of said members excepting the uppermost movably depends from the next vertically adjacent member.

2. In a damper, the combination of a plurality of vertically adjacent members, longitudinally extending grooves on contiguous edges of said members, means engaged by said grooves whereby said members are dependently supported, and means removably securing said last named means against movement relatively to said members.

3. In a damper, the combination of a plurality of vertically adjacent members, T-shaped longitudinally extending grooves on the contiguous horizontal edges of said members, and I-shaped members in said grooves connecting said members.

4. In a damper, the combination of a plurality of vertically adjacent members, T-shaped longitudinal grooves extending throughout the contiguous edges of said members, I-shaped connecting members in said grooves, and means associated with the uppermost of said members whereby said damper may be dependently supported.

5. In a damper, the combination of a plurality of vertically adjacent members, T-shaped longitudinal grooves extending throughout the contiguous edges of said members, I-shaped connecting members in said grooves, and means securing said I-shaped members in said grooves against axial movement relatively to said members.

FRANK F. JACKSON.
